C. A. Rowell

UNITED STATES PATENT OFFICE.

CHARLES HENRY FREER, OF BLUE EARTH CITY, MINNESOTA.

STRAP-BUCKLE.

SPECIFICATION forming part of Letters Patent No. 369,705, dated September 13, 1887.

Application filed February 26, 1887. Serial No. 229,024. (No model.)

To all whom it may concern:

Be it known that I, CHARLES HENRY FREER, a citizen of the United States, residing at Blue Earth City, in the county of Faribault and 5 State of Minnesota, have invented a new and useful Improvement in Strap-Buckles, of which the following is a specification.

My invention relates to an improvement in strap-buckles for harness; and it consists in a 10 certain novel construction and arrangement of parts for service, fully set forth hereinafter and claimed.

The object of the invention is to provide a buckle which may be more easily applied to 15 and removed from the straps of the harness than the ordinary buckle.

In putting harness together it is often necessary to apply a buckle to the center of a long strap, and in order to do so it is necessary to 20 pass one-half of the length of the said strap through the said buckle, and to reverse the operation in removing the buckle. This inconvenience is particularly noticeable in adjusting "crotch-lines," "martingales," "re- 25 turn-straps," &c.; and it is my object to provide means to obviate this inconvenience.

In the accompanying drawings, Figure 1 is a perspective of a strap provided with my improved buckle. Fig. 2 is a central trans- 30 verse section thereof through the tongue-bar. Fig. 3 is a perspective view of the buckle with the parts detached. Fig. 4 is a side elevation of the buckle with the long strap looped and passed into buckle and tongue-bar on the end 35 of short strap about to be inserted. Fig. 5 is a similar view with the tongue-bar inserted, turned, and about to be drawn down into place in the body of the buckle. Fig. 6 is a detail view of the body of the buckle.

Referring to the drawings, in which similar letters denote corresponding parts in all the figures, A designates the body or frame of the buckle, comprising the ends *a* and the sides *a'*, cast integrally, either one or both of said 45 ends having a small groove, *A'*, therein to receive the end of the tongue when the buckle is properly fixed on a strap.

B represents vertical grooves or slots formed in the inner sides of the sides *a'* of the buckle- 50 frame, which grooves are open at the upper end and extend only partly down the depth of

the buckle, thus being closed at the lower ends. In the said grooves or slots are journaled the ends of the tongue-bar C, which is formed integrally with the tongue D and turns therewith. 55

It will be seen that the shape of the buckle is very similar to those now in general use, the ends of the tongue D resting in the shallow groove A' in the end of the buckle-frame, the difference being that the tongue and 60 tongue-bar are formed integrally, and they are movable. (It will be remembered that the tongue-bar in the old forms of buckles are secured rigidly in the frame, and the tongue is pivoted thereon or formed with a loop in 65 the rear end to surround the said tongue-bar and turn thereon.)

To remove the strap from the buckle, push the loop of the long strap up through the frame of the buckle between the ends thereof, thereby 70 withdrawing the tongue D from the perforations in said strap, raise the tongue-bar, to which the end of the short strap is attached, by pressing upwardly upon the said short strap until the ends of said bar are free from the 75 grooves B, turn said tongue-bar to prevent the ends thereof from re-engaging in the slots, draw the tongue-bar out of the frame of the buckle, and the loop of the long strap, not having any cross-bar (or tongue-bar) to hold 80 it in, will also slip out of the frame, and the buckle will be free.

To apply the buckle to any point of the strap, it is only necessary to exactly reverse the operation: Pass a loop formed in any part of the 85 strap up through the buckle-frame, as clearly shown in Fig. 4, insert the tongue-bar in a position longitudinally with the length of the frame by means of the short strap, turn said tongue-bar into its proper transverse position, 90 and draw it down to cause the ends thereof to engage in the slots or grooves B, and the buckle is ready for use.

It is obviously a great saving of time to obviate the necessity of passing the long strap 95 through the buckle over the stationary tongue-bar, especially as it sometimes happens that, in order to place a buckle at the proper intermediate point of the length of a long strap, it is necessary with the old forms of buckles 100 to detach several other previously-secured buckles therefrom; but with my improved

buckle a double driving rein or line can be changed to a single line, or vice versa, without altering in any manner the other parts of the lines or harness, and it can also be accomplished in a moment, thus taking very much less time than the said old forms to attach.

A further advantage of my buckle lies in the fact that the tongue may be reversed in the frame—that is, turned end for end—thus causing the tongue to close down on the end piece of the frame at the opposite end of the said frame, and in effect reversing the buckle without taking the buckle-frame from the strap. (This of itself is a great advantage.) Also, the facility with which the buckle may be removed from and applied to the strap makes it of advantage to remove said buckles while oiling or cleaning the harness, thus saving them from being oiled or blackened. Further, the buckle may be made more cheaply than the ordinary buckle in which the tongue-bar is rigid in the frame, for the reason that the said frame must be cast and the bar and tongue each applied and fixed to said frame after the casting, thus causing a double handling of the frame, while with my buckle, the frame and the tongue-bar and tongue are each cast in separate parts and finished, and there is no attachment of the parts thereafter. This saving of a second handling is a considerable saving of time and therefore expense in the manufacture of the buckles, and is a great point of advantage in my improved buckle.

My reason for forming the tongue integrally with the bar, as will be readily seen, is that there is no necessity for the tongue to be movable on the said bar, as it is journaled in the grooves in the frame and therefore turns freely. Thus greater simplicity is gained by casting said parts integrally; but further than this, by forming the said tongue and bar as described, there will be less possibility of the tongue becoming loose in the buckle and ren-

dering it worthless, and there is no chance for lateral play of the said tongue.

It will be understood that I do not wish to limit myself strictly to the precise construction of the buckle-frame or of the slots in said frame, as herein shown and described, as slight variations may obviously be made in said details without departing from the spirit and intent of the invention.

Having thus described my invention, what I claim, and desire to secure by Letters Patent of the United States, is—

1. A buckle having a frame, A, constructed substantially as described, combined with the detachable tongue D, adapted to be reversed to operate the buckle in either direction, substantially as described.

2. A buckle having the frame provided with the slots B, combined with the tongue D and tongue-bar C, the ends of which are adapted to be received in the said slots, substantially as described.

3. A buckle having the frame A, provided with the vertical slots on the sides, combined with the tongue-bar C, journaled at the ends in said slots, and the tongue D, formed integrally with the said bar, substantially as described.

4. A buckle having the frame A, provided with the vertical slots B in the sides, said slots being open at the upper ends and closed at the lower ends, combined with the tongue-bar to be journaled at the ends in the said slots and the tongue formed integrally with the said bar, substantially as described, for the purpose hereinbefore set forth.

In testimony that I claim the foregoing as my own I have hereto affixed my signature in presence of two witnesses.

CHARLES HENRY FREER.
